CIGARETTE LIGHTER

Keith Soane, Broadbridge, England, assignor to Ronson Corporation, Woodbridge, N.J.

Filed Nov. 10, 1970, Ser. No. 25,922

Claims priority, application Great Britain May 11, 1970

Term of patent 14 years

Int. Cl. D27—05

U.S. Cl. D48—20

FIG. 1 is a perspective view of a cigarette lighter showing my new design;

FIG. 2 is a side elevational view thereof;

FIG. 3 is a rear elevational view thereof;

FIG. 4 is a front elevational view thereof;

FIG. 5 is a top plan view thereof;

FIG. 6 is a bottom plan view thereof.

I claim:

The ornamental design for a cigarette lighter, substantially as shown and described.
